UNITED STATES PATENT OFFICE.

ALFRED M. BROWN, OF WORCESTER, MASSACHUSETTS.

BEVEL.

SPECIFICATION forming part of Letters Patent No. 445,520, dated January 27, 1891.

Application filed April 10, 1890. Serial No. 347,334. (No model.)

To all whom it may concern:

Be it known that I, ALFRED MERRILL BROWN, of Worcester, in the county of Worcester and State of Massachusetts, have invented a new and useful Improvement in Bevels, of which the following is a full, clear, and exact description.

My invention relates to an improved bevel, and has for its object to provide a simple and durable tool especially useful to carpenters and stair-builders, capable of use not only for obtaining a correct single or double bevel, but which may also be employed to gage the length and breadth of the work, or as a square; and a further object of the invention is to so construct the tool that the various adjustments may be conveniently and expeditiously made.

The invention consists in the novel construction and combination of the several parts, as will be hereinafter fully set forth, and pointed out in the claims.

Reference is to be had to the accompanying drawings, forming a part of this specification, in which similar figures and letters of reference indicate corresponding parts in all the figures.

Figure 1 is a plan view of the tool when used as a bevel. Fig. 2 is a plan view of the body of the tool with the bevel-arms detached for use as a gage. Fig. 3 is a side elevation of the tool with the bevel-arms applied thereto. Fig. 4 is a plan view of the tool when in position for use as a square. Fig. 5 is a transverse section through the adjusting and connecting devices of one of the bevel-arms. Fig. 6 is a vertical section through one of the body clamping and guiding cleats, and Fig. 7 is a plan view of the upper tie-plate of the adjusting mechanism of the bevel-arm.

The body of the device consists of two bars 10 and 11, preferably rectangular in cross-section and of any desired length, each of which bars is provided in one side near its outer end with a recess 12. The bars are held to slide one upon the other and are guided in said movement by two guide-clips 13 and 14. The guide-clip 13 consists of a perpendicular member a , at the ends of which horizontal members a' a^2 are formed. The length of the member a is practically equivalent to the combined thickness of the body-

bars, and the length of the members a' and a^2 correspond, essentially, with the width of the side bars. The upper member a' is slotted to receive a screw 15, secured in the upper body-bar, and the lower member is provided with an upwardly-extending lip a^3 , which engages with one side face of the lower body-bar. The clip 14 is practically the same in construction with the clip 13; but the vertical member b thereof is longer than the corresponding member of the clip 13, and the upper member b' is provided with a downwardly-extending lip b^2 , adapted for engagement with the face of the upper body-bar 65 opposite to the face of the lower bar, with which the lip a^3 of the clip 13 contacts, and in the lower member b^2 of the clip 14 a slot is made to receive a screw 16, attached to the under face of the lower bar. The under face of the upper horizontal member b' of the clip 14 does not contact with the upper surface of the upper body-bar, and is provided with a threaded aperture, through which a set-screw 17 is downwardly passed, 75 which set-screw has a bearing upon a clamp-plate 18, the said plate being provided with an upper socket to receive the set-screw and a lower bearing-face. The clamp-plate is further provided at opposite sides with upwardly-curved fingers 19, which clamp the side surfaces of the upper member of the clip, as best shown in Fig. 3. By means of these two clips the body-bars are guided in their movements one upon the other, and when they 85 have been properly adjusted they may be securely held in the adjusted position by manipulating the set-screw 17 in such manner as to cause the clamp-plate 18 to bear down tightly against the upper body-bar, and thereby compress the two bars between the said clamp-plate and the lower member of the clip, as illustrated in Fig. 6.

To the recessed end of each of the body-bars a bevel-arm A is adapted for adjustable attachment. These arms may be of any desired length, and are so constructed that the blade-section thereof, which constitutes the body of the arm, is provided with a beveled upper surface and a flat under or bearing 95 surface. From the center of the body portion of the arms a rearwardly preferably

spider-like extension 20 is projected, and the arms of the said extension are united at the rear with a disk 21, (best illustrated in Fig. 3,) which disk is provided with an angular upwardly-extending flange 22 and a central aperture countersunk upon the under race of the disk. (See Fig. 5.)

The arms A at each end of the tool are preferably of the same length and are alike in construction, except that the extension 20 of the arm adapted for attachment to the bar 10 is curved upwardly, as shown in Fig. 3. In connection with the arms a clamping mechanism B is employed. (Best illustrated in the section, Fig. 5.) This clamping mechanism consists of an upper tie-plate 23, a lower tie-plate 24, and a central screw-bolt 25, provided with a lock-nut 26, which bolt passes through central apertures in the plates, and of a set-screw 27. The upper tie is provided with a transverse channel 28 in its under face of sufficient depth and width to receive the upper surface of the body-bar to which it is to be applied, and by reason of the channel being formed in the upper tie-plate the said tie-plate extends downward in contact with the side edges of the said bar.

At one side of the channel 28 the material of the plate is preferably reduced in width, as shown at d, Fig. 7, and in dotted lines, Fig. 1, and in the outer extremity of this reduced portion of the upper tie-plate a threaded aperture is produced, in which the set-screw 27 is entered, and between the aperture receiving the set-screw and the central aperture d² a recess d' is formed in the under face of the upper tie-plate. The aperture d² is unthreaded, and one side wall thereof is made flat, for a purpose hereinafter explained. The lower tie-plate 24 is also provided with a channeled surface corresponding in position with the equivalent surface of the upper plate, the channeled surface of the lower plate being adapted to receive the underface of the body-bar. The aperture in its channeled surface corresponds in location with the aperture d² of the upper plate, and the said lower tie-plate is made long enough to enable the lower end of the set-screw 27 to bear against the same at one side of the channel, and between the bearing-surface of the set-screw and the aperture in the lower tie-plate a stud 29 is formed upon the upper face of the latter, the upper end of which stud is adapted to enter the recess d' in the upper tie-plate. The stud is surrounded by a coil-spring 30, having a bearing upon the opposed surfaces of the two plates, as best shown in Fig. 5. The screw 25 is passed through the countersunk aperture in the spider-extension of the bevel-arm, and is also passed upward through the apertures in the tie-plates and beyond the upper plate, and upon the upper end of this screw a lock-nut 26 is located, having a bearing upon the upper plate. The threaded portion only of the screw passes through the upper tie-plate, and in order to prevent the said screw from

turning its threaded end at one side is made flat to bear against the flattened portion of the wall of the aperture d² in the upper tie-plate. When the arm is attached to the body-bar, that portion of the screw between the two plates fits into the recess 12 of the body-bar. When the device is used as a bevel, either arm may be placed in any desired position by loosening the set-screw 27, and when the proper position of the arm is obtained the set-screw is screwed downward to a bearing upon the extension of the lower tie-plate, whereupon the said tie-plate is forced downward to a frictional contact with the flange 22 of the spider-like extension 20 of the bevel-arm, and the said arm is prevented from turning.

The stud 29 serves to assist in preventing lateral movement of the tie-plates, and the spring 30 tends to force the two plates apart when the lock-nut 26 is unscrewed, thus rendering the detachment of either one of the bevel-arms from the body-bar very convenient when such detachment is desired.

When the device is to be used as a gage, both arms are removed, as illustrated in Fig. 2, and when used as a square the screw 15, secured to the upper body-bar, is removed, for instance, whereby the lower body-bar may be slid from beneath the upper bar, and the clip 13 will readily fall from engagement with the bar. The set-screw 27 of the arm attached to this bar is then loosened and the bar carried over the bevel-arm to extend at a right angle across the bevel-edge thereof, as shown in Fig. 4, and when the body-bar is in this position the set-screw is tightened. Thus a perfect square is obtained.

While specific construction has been shown and described, equivalent construction may be employed without departing from the spirit of the invention.

Having thus described my invention, I claim as new and desire to secure by Letters Patent—

1. In an implement of the character described, the combination, with the two bars 10 11, overlapping at their inner ends and provided near their outer ends with notches 12 115 12, of the U shaped clip 13, embracing the two bars and having a lip a³ on the forward end of its lower member and a slot in its upper member, a screw 15, extending from the bar 10 through said slot, a second similarly-formed clip 14, the lower member of which is slotted and the upper member provided with a lip b³ and a vertical set-screw 17, the screw 16, passing through said slot into bar 11, and the plate 18 between the upper face of the bar 10 and the inner face of the member b', and having fingers 19 19, holding it to said member b', substantially as set forth.

2. The combination, with the two bars adjustably connected at their inner ends, of the bevel-arms at the ends thereof, each having a central disk 21, the upper and lower channeled tie-plates 23 24, embracing the ends of said bars, a screw 25, passed through the disks and

each pair of tie-plates, and a set-screw 27, passed down through the upper tie-plate of each pair parallel with screws 25 and bearing on the lower tie-plates to bind them to the 5 disks 21, substantially as set forth.

3. The combination, with a bar, of a bevel-edge A, provided with a central disk 21 on its rear edge, having an annular flange 22 on its upper side, channeled tie-plates embracing 10 the bar, the lower of the two plates resting on said flange 22, a screw passing through the said disk and plates, and a second screw 27, passed down through the upper tie-plate and bearing at its lower end on the other plate to 15 bind it to the said flange 22, substantially as set forth.

4. An implement of the character described, consisting in two bars adjustably connected at their inner ends and each having a gage-notch 12 in its forward edge, bevel-edges A A, having central pivot-apertures, channeled tie-plates embracing the ends of the bar, pivot-screws passed through said apertures, notches 20 12, and the tie-plates, and the adjusting-screws

passed through the outer tie-plates and bearing at their inner ends on the lower tie-plates to bind them against the bevel-edges, substantially as set forth. 25

5. In a tool of the character described, the combination, with the bar, of channeled tie-plates contacting with the upper and lower faces of the bar, the upper tie-plate being provided with a recess and the lower plate with a spring-surrounded stud adapted to enter the recess, a set-screw held to turn in the 30 upper plate and contact with the lower plate, a bevel-arm having one straight edge and a rear central extension, a screw having one of its sides flattened passed through the extension of the bevel-arm, the upper and lower 35 tie-plates, and in contact with the bar, and a lock-nut located upon the upper projecting end of said screw, as and for the purpose specified. 40
